CLAIM

The ornamental design for a tumbler seal rack or the like, substantially as shown.

DESCRIPTION

FIG. 1 is a top perspective view of a tumbler seal rack
or the like showing my new design;

FIG. 2 is an end elevational view thereof;

FIG. 3 is a side elevational view thereof;

FIG. 4 is a top plan view thereof;

FIG. 5 is a bottom plan view thereof; and

FIG. 6 is a cross-sectional view taken along line 6—6 of
FIG. 4.
